UNITED STATES PATENT OFFICE.

CHARLES E. STELLER, OF MILWAUKEE, WISCONSIN.

TRANSOM-LIFTER.

SPECIFICATION forming part of Letters Patent No. 317,036, dated May 5, 1885.

Application filed January 21, 1885. (No model.)

To all whom it may concern:

Be it known that I, CHARLES E. STELLER, a citizen of the United States, residing at Milwaukee, in the county of Milwaukee and State 5 of Wisconsin, have invented certain new and useful Improvements in Transom-Lifts; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to improvements in transom lifts and locks, and pertains to the construction of the lifting-bar, the devices for locking it at its several places of adjustment, and to the construction of the supporting- 20 guideways by which the lifting-bar is attached to the side of the doorway.

My invention is further explained by reference to the accompanying drawings.

Figure 1 represents a perspective view of 25 my device attached to the transom and doorway. Fig. 2 is a perspective view of my invention removed from the door and transom. Fig. 3 is a perspective view of one of the retaining-keepers by which the lifting-rod is 30 held in place. Fig. 4 represents a front view of the retaining-keepers and the screw for locking the lifting-rod at the desired places of adjustment. Fig. 5 is a side view, part in section, of the lifting-rod and device for locking it.

35 Like parts are represented by the same reference-letters throughout the several views.

A is the transom, which is attached at the upper edge to the doorway.

40 B is the transom-arm. The arm B is made of a single piece of flat metal which is set into and secured by screws to the end of the transom.

C is the lifting-bar, which is also formed of 45 a single piece of flat metal which is arranged edgewise to the door-frame and transom, so that the strain of lifting the transom is brought to bear against the edge of the bar, whereby it is obvious that the bar so formed and so 50 arranged is capable of supporting a much heavier weight in proportion to its heft than the ordinary round rods heretofore used. The lift-

ing-bar C is retained edgewise in the required position by the keepers D and E. The keeper D is provided with vertically-arranged fastening-plates a, horizontal rod-bearing b, retaining-lugs c, and bracket d, having open way g for the reception and passage of the lifting-bar. The opening g, formed in the bracket d, is made for convenience in molding, 60 and also to permit the upper joint of the lifting-bar to be passed through it preparatory to being attached to the door-frame.

It is obvious that by the peculiar construction of the keepers they are adapted to perform the threefold purpose of supporting, 65 guiding, and retaining the lifting-bar, and they are also by such form adapted to be readily formed by casting without additional labor. The lower keepers, E E, are formed 70 to closely fit the lifting-bar, so as to properly guide the same, and being open at their base they permit the lifting-bar C to be readily inserted. The lifting-bar C is locked at any 75 desired point of adjustment by the set-screw F, which is located midway between the lower keepers, E E, and is interposed between the lifting-bar C and the door-frame A'. The thread of the screw F operates in a nut or socket, F', which is inserted in the front surface of the door-frame, and is provided with a fastening-plate, a', through which small 80 screws are inserted into the door-frame at d' d', to prevent said nut from turning with the adjusting-screw. The adjusting-screw F is 85 provided with radial arms b', by which it is turned when fastening or releasing the lifting-bar. The screw F serves as a supporting-bearing to the lifting-rod, and prevents it from coming in contact with the door-frame. When 90 the set-screw is turned outward it bears against the inner edge of the lifting-bar, whereby the outer edge of the lifting-bar is pressed against the inner surface of the keepers. The distance between the keepers E E is such as to permit 95 of easy access to the adjusting-screw. By an inverse movement of the adjusting-screw the lifting-bar C is released.

In transom-lifts as heretofore constructed the lifting-bar has been locked by contact of 100 the point of the screw with the convex surface of the lifting-rod.

By my improvement it is obvious that I have so increased the bearing-surface of the

locking device as to rigidly retain the lifting-bar at any desired point of adjustment solely by the frictional contact of the bearing-surfaces without the aid of notches or depressions 5 in the surface of the lifting-bar. The arms *b* of the set-screw are of such length as to be easily grasped when desired to adjust the rod, and, owing to the leverage thus obtained upon the set-screw, it is very easily turned, and but 10 slight power is required to permanently lock the heaviest transom either closed or at any point of adjustment. The upper end of the bar *C* is provided with a hole, *J*, for the reception of a hook, *O*, on one end of the link *K*. 15 The hook *O* upon the opposite end of the link *K* engages in the hole *M* of the lifting-arm *B*. It will be seen that by the simplicity of the construction of the lifting-bar and the link *I* am enabled to attach them to each other, with- 20 out nuts or screws, simply by inserting the hooks through the holes in the upper end of the lifting-bar and transom-arm, thus mate- rially reducing the labor of attaching the lift; also that the single parts of the device may be 25 packed and shipped separately, and when put up all the parts, including the keepers and transom-arm, may be readily connected with- out the aid of skilled labor. All the parts are 30 also made reversible, and may be attached to either side of the transom.

On transoms suspended by hinges at their upper edges the lifting-bar *C* projects above the upper keeper, *D*, and in order to resist the backward pressure upon the upper end of the 35 lifting-bar, which is caused by the gravity of the transom, I preferably interpose between said lifting-bar and the door-frame the guideway-bar *N*, having lugs *g'*, which serve as a bearing along which the upper end of the lift- 40 ing-bar *C* moves, and against which it is caused to bear slightly as the transom is opened and closed. With transoms centrally pivoted the guideway *N* is not required, as the lifting-bar thus formed is sufficiently rigid to operate it 45 without bending. The lower end of the lift- ing-bar is provided with any suitably formed handle; but I prefer the form shown in Fig.

2, consisting of the rectangular pieces *B' B'*, which are riveted to the respective flat surfaces of the lifting-bar. By this form of lift, 50 in connection with the form of bar shown, it is impossible for the lifting-bar to be sprung sufficiently to bring the lift in contact with or to mar the door-frame.

Having thus described my invention, what 55 I claim as new, and desire to secure by Letters Patent, is—

1. In a transom-lift, the combination, with the retaining-keepers affixed to the doorway, and the connecting-link of the transom, of the 60 flat rectangular lifting-bar *C*, arranged edge- wise to the door-frame, substantially as and for the purpose set forth.

2. In a transom-lift, the combination, with the lifting-bar as secured to the door-frame 65 with one or more retaining-keepers, of a screw interposed between said bar and said door- frame and operating in a nut or socket set into said frame beneath said bar, substantially as set forth.

3. The combination, with the guide-bearing 70 *N*, interposed between the upper end of the lifting-bar and the door-frame, of the bar-retaining lugs *g'*, as set forth.

4. The combination, with the lifting-bar of 75 a transom-lift, of one or more keepers, *D*, having vertical fastening-plates *a*, horizontal rod- bearings *b*, and brackets *d*, provided with opening *g*, as set forth.

5. In a transom-lift, the combination, with 80 the lifting-rod *C*, of two or more retaining-keepers, *E*, open at their base, screw *F*, and one or more bearings interposed between said lifting-rod and the casing, said screw *F* and said bearings serving as a rear support to the 85 lifting-rod within said open keepers, as set forth.

In testimony whereof I affix my signature in presence of two witnesses.

CHARLES E. STELLER.
